ATTORNEY

UNITED STATES PATENT OFFICE.

AUGUST HILDT, OF NEW YORK, N. Y., ASSIGNOR TO L. DRYFOOS & CO., OF SAME PLACE.

DESIGN FOR THE ORNAMENTATION OF SKIRTS.

SPECIFICATION forming part of Design No. 18,100, dated February 21, 1888.

Application filed January 7, 1888. Serial No. 260,093. Term of patent 7 years.

To all whom it may concern:

Be it known that I, AUGUST HILDT, a citizen of the United States, and a resident of the city, county, and State of New York, have invented a new and original Design for Surface Ornamentation of Skirts, Linings, &c., of which the following is a specification.

My design is for the surface ornamentation of skirts, linings, and other similar articles; and it consists of parallel rows of oval-shaped figures arranged with the shorter diameters of the several figures of each row lying in the same line, with intervening rows of lozenge-shaped figures or parallelograms disposed with reference to such figures, all as will hereinafter more fully appear.

In the accompanying drawing I have represented in a single figure a portion (containing all the elements) of my design as it appears when applied to or upon the article or goods, dotted lines being employed to indicate stitches, and these lines being arranged or grouped in accordance with my design, this illustration being deemed sufficient for purposes of this specification.

For convenience of description the various parts of the design may be referred to as follows:

A A A indicate oval-shaped figures of any desired number, located one above the other, with the peripheries of the adjacent figures tangent to and touching each other and having the shorter diameter of all lying in the same vertical line.

B B B indicate oval shaped figures similar to the figures A A A, the same being similarly disposed to the latter and forming another vertical row parallel therewith. Any two rows of these figures are separated from each other by a distance equal to or about twice the length of the larger diameter of said figures, in order

that the intervening lozenge-shaped figures or parallelograms may be suitably proportioned. Any number of rows of such oval-shaped figures may be added, and thus the design made to cover any desired extent of surface.

Between the rows of oval-shaped figures A and B are straight lines, indicating stitching, which extend from the extremity of the horizontal diameters of the figures of one row to corresponding points on figures in the next row, not extending horizontally, nor yet to the figures next to the one above or below that in the same level, but to the second one above or below, as shown, the arrangement being such as to form a series of lozenges or parallelograms, as a b c d, touching each other and the figures in the manner shown. These lozenges will be varied in size by varying the size of the oval-shaped figures and the distance of the rows of such figures from each other. Between any two oval-shaped figures in the same level this arrangement affords two complete lozenges or parallelograms, and thus cover the entire space between them.

Having thus described my invention, what I claim as new, and desire to secure by Letters Patent of the United States, is—

The design for surface ornamentation of skirts, &c., herein described and shown, consisting of the parallel rows of oval-shaped figures arranged with the shorter diameters of the figures of each row all lying in the same line and the intervening rows of lozenge-shaped figures or parallelograms, substantially as described.

In testimony whereof I have hereunto set my hand this 5th day of January, 1888.

AUG. HILDT.
